INTERNAL GRINDING FIXTURE

Clement Booth, Cincinnati, and John E. Caster,
Willoughby, Ohio, assignors to Cincinnati
Grinders Incorporated, Cincinnati, Ohio, a
corporation of Ohio

Application May 31, 1935, Serial No. 24,286

9 Claims. (Cl. 51—3)

This invention relates to grinding machines and more particularly to attachments therefor.

One of the objects of this invention is to provide a grinding machine in which internal and external grinding operations may be carried out without changing the set-up of a work piece.

Another object of this invention is to provide an improved internal grinding attachment for cylindrical grinding machines.

10 A further object of this invention is to provide an internal grinding attachment which may be detachably applied to cylindrical grinding machines and in which, even when applied, the internal grinding wheel may be oscillated out of 15 working position so that the machine may be utilized for cylindrical grinding purposes without interference by said attachment.

An additional object of this invention is to provide an internal grinding attachment which is applicable to a cylindrical grinding machine 20 in such a manner that the same in-feeding mechanism for the grinding wheel and the same traversing mechanism for the table may be utilized with the internal grinding wheel.

25 Other objects and advantages of the present invention will be readily apparent by reference to the following specification considered in conjunction with the accompanying drawings illustrative of one embodiment thereof, but it will be understood that any modifications may be 30 made in the specific structural details within the scope of the appended claims without departing from or exceeding the spirit of the invention.

35 Referring to the drawings in which like reference numerals indicate like or similar parts:

Figure 1 is a front elevation of a machine embodying the principles of this invention.

Figure 2 is a plan view of the machine shown in Figure 1.

40 Figure 3 is a sectional view taken on the line 3—3 of Figure 1.

Figure 4 is a sectional view taken on the line 4—4 of Figure 1.

45 Figure 5 is a detailed section taken on the line 5—5 of Figure 2.

Figure 6 is a diagrammatic view of the power traversing mechanism for the table.

Figure 7 is a modified form of the invention.

In Figure 1 of the drawings there is shown a 50 plain cylindrical grinding machine comprising a bed 10 having guideways formed on the top thereof for receiving a reciprocating table 11 which may be provided with a headstock 12 and a tailstock 13 for supporting a work piece in operative 55 relation to an external grinding wheel 14. This

grinding wheel may be secured to the end of a spindle 15 which is journaled in a bearing housing 16 formed in a housing 17 carried by a cross slide 18 whereby the wheel may be adjusted relative to the work carried by the table. 5

The housing 17 may be pivotally mounted for rotation about a pin 19 carried by the cross slide 18 whereby the axis of the grinding wheel may be angularly adjusted with respect to the axis of reciprocation of the table which facilitates adjustment of the parts for grinding tapered surfaces. 10

The grinding wheel may be driven by a prime mover 20 mounted directly on the housing 17 and having a pulley 21 on one end in alignment 15 with a pulley 22 mounted on the end of spindle 15 opposite to the grinding wheel. These pulleys may be connected by a plurality of V-belts 23 as shown in Figure 5.

The pulley 21 may be supported on anti-friction 20 bearings 24 carried by the end of the motor shaft 25, the anti-friction bearings supporting the pulley for free rotation with respect to the shaft. 25

The end of the shaft has a bore 26 in which is 25 slidable a plunger 27 having a cross pin 28, the ends of which project through diametrically opposite slots 29 formed in the shaft 25 into engagement with a shiftable clutch member 30. 25

The end of plunger 27 has a hand wheel 31 and a plurality of grooves 32 engageable by spring 30 pressed balls 33 which constitute means for shifting the clutch member 30 into and out of engagement with clutch teeth 34 formed on one face of the pulley 21 and holding the parts in either position. This constitutes a start and stop clutch 35 for the grinding wheel 14. 35

The table may be reciprocated by power means comprising a prime mover 35 which may be mounted in a convenient place in the bed of the machine and connected through rate change gear 40 ing and reversing mechanism to the table.

This mechanism is more particularly shown in Figure 6 and comprises a drive shaft 36 which is connected by a chain and sprocket mechanism indicated generally by the reference numeral 37 to the prime mover 35. A start and stop friction clutch 38 may also be provided for connecting and disconnecting the prime mover with shaft 36. 45

The shaft 36 extends into a rate change box 39 and has a shiftable gear unit 40 splined thereon comprising gears 41, 42 and 43 selectively shiftable into mesh with gears 44, 45 and 46, the latter being carried by shaft 47. The shaft 47 also has a shiftable gear unit 48 comprising gears 49, 50 and 51 selectively shiftable into mesh with 55

gears 52, 53 and 54 mounted on shaft 36. By means of these two shiftable gear units, the shaft 47 may be rotated at any one of six different speeds by the prime mover. The rate change unit 39 may be mounted in a convenient relation to the prime mover at the rear of the machine and connected to a shaft 55 journaled in the front of the machine in parallel relation to shaft 47 by means of an intermediate shaft 56 which is connected at one end by bevel gearing 57 to the shaft 47, and at the other end by bevel gearing 58 to shaft 55. The final bevel gear 59 of the gearing 58 is actually mounted for free rotation on the shaft 55 and has integral therewith a spur gear 60 and clutch teeth 61 formed on the face of the spur gear. The shaft 55 has a shiftable gear 62 mounted thereon which has clutch teeth 63 on one face for engagement with clutch teeth 61 whereby the bevel gear 59 may be directly connected to shaft 55 for rotation thereof.

The gear 62 is also shiftable into mesh with a gear 64 of couplet 65 which has a relatively large gear 66 intermeshing with the relatively small gear 60 whereby when this connection is made the shaft 55 is rotated at a relatively slow speed compared to its speed of rotation when directly connected to gear 59. The shiftable member 62 may thus be termed a feed rapid traverse selector because when in one position the shaft 55 is rotated at a slow or feeding rate, and when in the other position the shaft is rotated at a relatively fast or quick traverse rate.

The shaft 55 also has mounted thereon for free rotation a pair of bevel gears 67 and 68 which have clutch teeth 69 and 70 formed on opposite faces thereof and selectively interengageable with clutch teeth formed on opposite faces of the shiftable reverser clutch member 71. The bevel gears 67 and 68 intermesh with bevel gear 72 secured to the end of shaft 73 which also has fixed therewith a worm 74 intermeshing with a worm gear 75 fixed to the end of vertical shaft 76.

The shaft 76, as shown in Figure 3, extends upward to the underside of the table 11 where it is provided with a pinion 77 which intermeshes with rack 78 secured to the underside of the table. The worm gear 75 is actually mounted for free rotation on the shaft 76 and is connectable thereto by means of clutch teeth 79 formed on one face of the worm gear, which are interengageable with clutch teeth 80 formed on the shiftable clutch member 81 which is splined on shaft 76.

When the clutch member 81 is shifted by its operating fork 82 secured to shaft 83 and having an operating handle 84 mounted on the front of the machine, the table is connected with the prime mover for actuation thereby at a plurality of different feed rates or at a rapid traverse rate or in opposite directions.

The clutch member 81 also has clutch teeth 85 formed on the opposite face thereof which are inter-engageable with clutch teeth 86 formed integral with bevel gear 87 whereby the bevel gear may be connected to shaft 76 and the power drive thereto disconnected. This bevel gear is utilized for manual actuation of the table from the rotatable hand wheel 88 which is secured to the end of shaft 89 and connected by the bevel pinion 90 to bevel gear 87.

There has thus been provided power operable and manually operable means for traversing the table and a selector has been provided for determining the manner of operation. Since the

reverser clutch 71 does not have a neutral position, the clutch 81 may also be moved to a third or intermediate position for disconnecting both drives from the table and it therefore serves as a stop clutch for the power drive.

The cross slide 18 may be moved toward and from the table by means of the following mechanism comprising a rack 91 secured to the cross slide, and a spur gear 92 intermeshing therewith, the spur gear being keyed to the end of a vertical shaft 93 which is journaled in the bed of the machine. The shaft 93 is rotated by a worm 94 secured to the end of shaft 95 and an intermeshing worm gear 96 keyed to the end of shaft 93. The shaft 95 extends through the front wall of the bed and is provided with a manually operating hand wheel 97. This shaft also has a pick-feed wheel 98 keyed thereto whereby the grinding wheel may be automatically fed toward the table at the end of each reciprocation thereof.

The following mechanism is utilized for operating the reverser and actuating the pick feed mechanism. A shift lever 99 is pivotally mounted at 100 on the front of the machine and has an integral depending arm 101 to the end of which is pivotally connected a horizontally reciprocable member 102 having a lost motion connection with the shifter member 103 of the reverser clutch 71. A rod 104 extends to opposite sides of the member 102 for connection to any well known form of load and fire mechanism, not shown, for completing the movement of the reverser clutch and which is operable in such a manner as to prevent this clutch from being shifted to a central or non-power transmitting position.

The member 99 is adapted to be alternately engaged by dogs 105 and 106 mounted in the usual manner in T-slots on the forward edge of the table.

The lever 99 also has a second lever 107 integral therewith which has a beveled end which engages a roller 108 rotatably mounted in one end of a bell crank 109. The bell crank is operatively connected to a vertically reciprocable plunger 110 in the end of which is pivotally mounted a pick feed pawl lever 111. When the lever 99 is rotated counter-clockwise, as viewed in Figure 1, the arm 107 moves in such a direction as to rotate the bell crank 109 in a clockwise direction and thereby depress the plunger 110 against the resistance of a spring 112 interposed between the lower end thereof and the frame of the machine. This positively actuates the pick feed pawl lever 111 in such a direction as to cause rotation of the shaft 95.

When the lever 99 is moved in a clockwise direction the spring 112 returns the plunger 110 in a vertical direction whereby the pick feed pawl lever will obtain a new grip on the pick feed wheel 98. Thus the pick feed mechanism is operated once for each reciprocation of the table and simultaneously with the reversal thereof.

As shown in Figures 3 and 4, a bracket 113 is provided for detachable connection to the top of the bearing housing 16 as by means of screws 114 for supporting an internal grinding wheel. This bracket has a pair of bosses 115 and 116 through which passes a rod 117 for pivotally supporting a swinging arm 118 on the end of which is formed a spindle housing 119. A spindle 120 is journaled in this housing and has means for detachably supporting an internal grinding wheel 121. This spindle also has a pulley 122 connected by belt 122' with a pulley 123 supported on an 70

idler shaft 124 journaled in the end of the arm 118 in adjacent relation to the pivot rod 117. The shaft 124 has a second pulley 125 connected by belt 128' with a large drive pulley 126 secured 5 to the end of the armature shaft 25 of prime mover 20.

When the arm 118 is swung downward to the position shown in Figure 3, means are provided in the form of bolts 127 for rigidly securing the 10 arm 118 in fixed position and thereby holding the grinding wheel 121 in fixed relation to the work. These bolts are slideable in T-slots 128 formed in the housing 16 whereby they may be loosened and quickly removed to permit elevation 15 of the arm 118 to its dash and dot line position shown in Figure 4.

It will be noted from Figure 4 that the shaft 124 moves in an arcuate path about the center 117 when the arm 118 is swung to its upward position. It will also be noted that the shaft 124 moves toward the center of the motor shaft 25, thereby loosening the tension on the belt 128' which interconnects pulleys 126 and 125 for rotation by the prime mover 20. Thus the mere 25 elevation of the arm 118 automatically interrupts the transmission of power to the internal grinding wheel.

Since the internal grinding wheel is carried by the housing 17, it will be noted that the same 30 infeed mechanism for the external grinding wheel 14 may be utilized for feeding the internal grinding wheel laterally into engagement with the work, and since the work can be mounted on the same table and in the same position for 35 internal grinding as for external grinding, the same mechanism is utilized for traversing the work with respect to the internal grinding wheel as is used for traversing the work with respect to the external grinding wheel. It thus follows 40 that with one set-up of the work piece both internal and external surfaces may be ground thereon, thus insuring that these surfaces are concentric with one another.

For internal grinding operations, the work 45 piece such as 129 is supported in a chuck 130 which may be secured to the face plate 131, the latter being adapted to be rotated by a prime mover 132 carried by the headstock.

In Figure 7, a modified form of the invention 50 is shown in which a separate electric motor 133 is mounted directly on the detachable bracket and the belt 122', which drives the internal grinding wheel, now passes around the motor pulley 134. The motor may be mounted with its axis 55 concentric with the axis of the pivot shaft 117 so that the belt will not loosen when the arm is raised as it is not necessary with this arrangement to loosen or remove the belt to stop the internal grinding wheel.

60 If plain cylindrical grinding operations are to be performed, the work may be mounted between centers carried by the headstock and tailstock and the internal grinding attachment may be retracted to its dash and dot line position shown 65 in Figure 4 and the cylindrical grinding operation carried out without interference therefrom.

There has thus been provided an improved 70 grinding machine for the purposes aforesaid in which both internal and external grinding operations may be carried out to produce surfaces concentric with one another and in which the internal grinding wheel may be retracted from working position, thereby conditioning the machine for performing external cylindrical operations without interference therefrom.

What is claimed is:

1. In a grinding machine having a bed, a work table reciprocably mounted upon the bed, and a spindle housing adjacent the bed, the combination of means for supporting an internal 5 grinding wheel comprising a bracket attached to said housing, a swinging arm pivotally mounted on said bracket, a spindle journaled in the end of said arm and carrying an internal grinding wheel, means to limit the swinging movement of said arm in one direction to position the internal grinding wheel in a working position relative to the work support, and means to positively secure said arm to said housing whereby said internal grinding wheel will be 15 positively held while in a working position.

2. In a grinding machine having a support, a work table reciprocably mounted upon the support and a grinding wheel housing movable toward and from the work support, the combination of means for supporting another grinding wheel in operative relation to the work support including a bracket detachably mounted on the housing, a arm pivotally mounted on the bracket, a grinding wheel spindle journaled in the end of the arm, a power shaft located on the side of the pivot opposite to the grinding wheel spindle, pulleys on the power shaft and spindle, an idler shaft journaled in the arm adjacent to the pivot for movement thereabout upon movement of the arm, a first pulley mounted on the idler shaft and operatively connected to the pulley on the spindle, a second pulley mounted on the idler shaft and connected by power transmitting band to the pulley on the power shaft, said idler shaft being movable in a first direction upon movement of the arm to a working position to cause tightening of the power belt, and in a second direction to loosen the power 40 belt and disconnect the drive to the grinding wheel.

3. In a grinding machine having a reciprocable work table, means thereon for rotating a work piece and a cross slide movable toward and from the work table, the combination of a prime mover mounted on said cross slide, a housing carried by the slide, a grinding wheel spindle journaled in the housing and having a driving pulley attached thereto, an internal grinding attachment 50 secured to said housing and including a driving pulley, said prime mover consisting of an electric motor having an armature shaft projecting at opposite ends thereof, means secured to one end of said shaft and lying in the plane of one 55 of said drive pulleys for actuation of one grinding wheel, means secured to the opposite end of said armature shaft and lying in the plane of the other pulley for actuation of the internal grinding attachment.

4. In a grinding machine, the combination with a reciprocable work table having means for rotatably supporting a work piece, the combination with a slide movable toward and from the table and having a grinding wheel journaled 65 therein, of a bracket detachably mounted on the slide, a power shaft carried by the bracket, an arm pivotally mounted on the bracket and having an internal grinding wheel spindle journaled in the free end thereof and motion transmitting 70 means coupling the power shaft to said spindle.

5. In a grinding machine, the combination with a reciprocable table, and a slide movable toward and from the table having an external 75 grinding wheel spindle journaled therein, of a

- bracket detachably mounted on the slide, an arm pivotally mounted on said bracket and having an internal grinding wheel spindle journaled in the free end of the arm for positioning an internal grinding wheel in a working position with respect to said table, a motor carried by said bracket with its axis coaxial with the pivot axis of the arm, motion transmitting connections coupling the motor for rotation of said internal grinding wheel spindle, and means for locking the arm to the slide independently of the connection of the bracket thereto.
6. The combination with the wheel head unit of an external grinding machine having a pair of angularly related seats formed thereon, of an internal grinding attachment for application thereto including a bracket portion, means to secure the bracket portion in interengaging relation with one of said seats, a pivot carried by the bracket portion, an arm oscillatable on the pivot, said arm being formed with a seat for interengagement with the other seat of the wheel head when in one position of adjustment about its pivot, a supplemental grinding wheel spindle journaled in the arm, and means for securing the arm to the wheel head with their seats interengaged whereby the spindle will be rigidly supported in definite position relative to the wheel head.
7. The combination with the wheel head unit of an external grinding machine having a pair of angularly related seats formed thereon, of an internal grinding attachment for application thereto including a bracket portion, means to secure the bracket portion in interengaging relation with one of said seats, a pivot carried by the bracket portion, an arm oscillatable on the pivot, said arm being formed with a seat for interengagement with the other seat of the wheel head when in one position of adjustment about its pivot, a supplemental grinding wheel spindle journaled in the arm, means for securing the arm to the wheel head with their seats interengaged whereby the spindle will be rigidly supported in definite position relative to the wheel head, a prime mover supported on said wheel head, and driving connections between the

prime mover and spindle operative to effect rotation of the spindle when the arm is secured in operative position.

8. An internal grinding attachment for application to the wheel head of a cylindrical grinding machine including a bracket portion for attachment to the machine, an arm mounted on the bracket for oscillatory movement relative thereto into and out of operative engagement, said arm being formed with an attaching portion remote from its connection with the bracket for direct engagement with the wheel head, means for securing said portion of the arm direct to the wheel head to maintain the arm in definite position with respect thereto, an internal grinding spindle journaled in the arm, a power transmitting member carried by the arm in eccentric relation to its oscillatable connection with the bracket, and a prime mover coupled with the spindle of the arm by way of said power transmitting device whereby oscillation of the arm about its pivot into operative grinding position will effect positive driving connection of the prime mover and spindle and the securing of the arm to the wheel head will maintain the parts in proper power transmitting relationship.

9. In mechanism of the character described, the combination with the wheel head, of an external cylindrical grinder including a grinding wheel spindle journaled thereon, of an auxiliary attachment therefor including a bracket applicable to the wheel head, means for securing the bracket to the wheel head, an arm pivoted to the bracket, an auxiliary grinding wheel spindle carried by the arm, means for securing the arm in one pivotal adjusted position direct to the wheel head, a prime mover carried by the wheel head, a first series of power transmitting connections from the prime mover to the first wheel spindle, a second series of driving connections from the prime mover to the second spindle, and independent means for determining the ineffectiveness of such connections as respects the individual spindles.
